UNITED STATES PATENT OFFICE.

JOHN M. ANGLE AND WILL R. LYNN, OF ALLEN, TEXAS.

TURNTABLE ATTACHMENT.

Application filed July 1, 1922. Serial No. 572,345.

To all whom it may concern:

Be it known that we, JOHN M. ANGLE and WILL R. LYNN, citizens of the United States, residing at Allen, in the county of 5 Collin and State of Texas, have invented new and useful Improvements in Turntable Attachments, of which the following is a specification.

This invention relates to cotton gin 10 presses, and has for its primary object, the provision of means for revolving the turn table of the press by motive power, and automatically stopping the table at each half revolution.

More specifically stated, the invention 15 embodies amongst other features, a belt driven shaft, supporting a fixed pulley and an idle pulley, the belt being automatically shifted from one pulley to the other incident 20 to the operation of the means which automatically stops the turn table, the latter being released and the belt again shifted by means of a manually operable element.

The nature and advantages of the invention 25 will be better understood when the following detailed description is read in connection with the accompanying drawings, the invention residing in the construction, combination, and arrangement of parts as 30 claimed.

In the drawings forming part of this application, like numerals of reference indicate similar parts in the several views, and wherein:—

Figure 1 is a top plan view of our improved turn table.

Figure 2 is a sectional view taken on line 2—2 of Figure 1.

Figure 3 is a sectional view taken on line 40 3—3 of Figure 2.

Figure 4 is a sectional view taken on line 4—4 of Figure 1.

Referring to the drawings in detail, 45 indicates the platform of a cotton gin press, which platform is provided with an opening in which the turn table 11 operates.

The table 11 is rotated by a vertical shaft 12 which is journaled in suitable bearings 13, and this shaft supports a gear wheel 15, which meshes with a worm gear 16 as shown. The latter mentioned gear is keyed to one end of a shaft 17, the latter being arranged at a right angle to the shaft 12 and secured to the opposite end of the shaft 17 and fixed thereto is a belt pulley 18. Also 50 journaled to the shaft 17 and arranged in

juxtaposition to the pulley 18 is an idle pulley 19. A belt 20 is arranged to operate either of the pulleys 18 or 19, the belt being driven from any suitable motive power, and at a point remote from the press. It is of course understood that when the belt is associated with the pulley 18, it rotates the shaft 17, which in turn revolves the table 11, and when it is associated with the idler 19, the shaft 17 remains stationary. In accordance with the present invention, the table 11 is adapted to be automatically stopped at each half revolution and incident to this operation, the belt 20 is automatically 60 shifted from the pulley 18 onto the pulley 19. For this purpose, I provide a horizontally disposed sliding bar 21, which operates in spaced parallel guides 22, which rise from a support 23, and projecting from this bar 21 are spaced parallel lugs 25 between which the belt 20 operates. The bar 21 is provided with a slot 26 to receive the bifurcated extremity 27 of a bell crank lever 28, this lever being fulcrumed as at 29 upon the support 23. The bar 21 supports a pin 30 which passes through the slot and also through the bifurcated extremity of the bell crank lever, so that when the lever is actuated, the bar 21 is reciprocated to shift the belt 20 as above stated. The opposite 70 end of this bell crank lever is connected with a vertically disposed rod 32, and the upper end of this rod is connected with one branch of a bell crank lever 34, which is fulcrumed on a bracket 35 secured to the underside of the platform 10. The lever 34 is secured to one end of a short shaft 36 which is journaled in the bracket 35, and this bell crank lever 34 is actuated in a manner to be hereinafter described to operate the belt shifting bar 21. Projecting from the other end of the short shaft 36 is an arm 37, which is connected with the adjacent end of a vertically disposed rod 38, the latter operating through an opening 39 in the platform 10 and projecting above the latter. The upper end of this rod 38 is received by an opening in a pivoted latch 40, this latch being pivoted upon the platform 10 and arranged to overlie the table 11, and when this latch is operated, it moves into engagement with a keeper 41, carried by the table 11, to hold the latter against movement. Surrounding the upper exposed portion of the rod 38 is a coiled spring 42, one end of this spring bearing against the 75 80 85 90 95 100 105 110

platform 10, and the opposite end bearing against the latch 40. This spring is compressed, while the table 11 is being rotated, and after the table has rotated half a revolution, this latch is actuated to engage its keeper simultaneously with the shifting of the belt 20 from the pulley 18 onto the pulley 19.

Secured to the underside of the platform 10, at a point adjacent the opposite side of the table 11 is a bracket 44, in which is journaled a short shaft 45, and this shaft has associated with one end thereof a bell crank lever 46. Connected with one end of this bell crank lever 46 is a manually operable element 47 which slides through an opening 48 in the platform 10, and is utilized to intermittently start rotation of the table 11, subsequent to each automatic stopping thereof. Projecting from the shaft 45 is a bar 49, and connected with this bar is a vertically disposed rod 50, which slides through an opening 51 in the platform 10, and has its upper end connected with a latch 52, which is pivoted upon the platform as at 53. This latch is arranged to be moved into engagement with a keeper 54 carried by the table 11 to hold the latter against movement after each half revolution of the table. A spring 55 surrounds the upper end of this rod and bears against the latch 52 to move the latter into active engagement with its keeper, incident to the shifting of the belt 20 from the pulley 18 onto the pulley 19.

Connected with the other branch of the bell crank lever 46 is a rod 56 which has its other end connected with one branch of a bell crank lever 57 which is on a bracket 58 secured to the underside of the platform. It will be noted that the bell crank 57 is arranged substantially in a plane at a right angle to the bell crank lever 46 with which it is connected. The other branch of this bell crank lever 57 is connected with the adjacent end of a rod 59 which extends along one side of the platform and has its other end connected with the adjacent branch of a bell crank lever 60, the latter being pivoted on a bracket 61 secured to the underside of the platform 10. The other branch of this bell crank lever 60 is connected with the adjacent branch of the bell crank lever 34 above mentioned, by means of a rod 63, and the arrangement of the parts just described is such, that when the bell crank lever 46 is actuated, it imparts movement to the belt shifting bar 21, thereby shifting the belt from the pulley 18 onto the pulley 19 or vice versa, depending of course upon the particular direction of movement of the bell crank lever 46. The bell crank lever 46 is automatically operated in one direction, that is to shift the belt from the pulley 18 onto the pulley 19, and for this purpose, I provide the table 11 with trip arms 65

which are secured to the underside of the table at diametrically opposite points. These trip arms are disposed to singly engage a trip lever 66, which is carried by one end of the shaft 45 at each half revolution of the table, and manifestly, when these parts contact, the shaft 45 is partly rotated, thereby actuating the bell crank lever 46 in the proper direction to shift the belt in the manner just described. As hereinabove pointed out, simultaneously with the operation of the bell crank lever for this purpose, the latch elements are moved into engagement with their respective keepers carried by the table 11, and the table is thus held against further rotation. When it is desired to permit further rotation of the table 11, it is only necessary to lift the manually operable element 47, thereby reversing the movement of the bell crank lever 46 and its associated parts, which of course reverses the movement of the belt shifting bar 21, which carries the belt from the idle pulley 19 onto the fixed pulley 18, whereupon the table is again put in motion.

While it is believed that from the foregoing description, the nature and advantages of the invention will be readily apparent, we desire to have it understood that we do not limit ourselves to what is herein shown and described, and that such changes may be resorted to when desired as fall within the scope of what is claimed.

What we claim is:

1. The combination with a turn table, and means for rotating the table including a belt driven shaft, and a fixed and idle pulley supported by the shaft, of a belt shifting bar mounted for reciprocatory movement, means for automatically moving the bar in one direction upon each half revolution of the table, to shift said belt from one pulley to the other, pivoted latch elements arranged to overlie the table, and actuated by the bar moving means to engage the table incident to the shifting of the belt as specified, and manually operable means for reshifting said belt and simultaneously releasing the table from said latch elements.

2. The combination with a turn table and means for operating the same including a belt driven shaft, and a fixed and idle pulley supported by the shaft, of a belt shifting bar mounted for sliding movement, means for automatically operating the bar to shift the belt from one pulley to the other with each half revolution of the table, said means including a shaft mounted for partial rotation, a connection between the shaft and said bar, a trip lever associated with the shaft, trip arms carried by the table and adapted to engage said lever, and a manually operable element for reversing the movement of said bar and reshifting said belt for the purpose specified.

3. The combination with a turn table, and means for rotating the same including a belt driven shaft, having a fixed and idle pulley mounted thereon, of a belt shifting bar 5 mounted for sliding movement, means for automatically moving the bar in one direction to shift the belt from one pulley to the other upon each half revolution of the table, said means including a shaft mounted 10 for partial rotation, a trip lever associated with said shaft, trip arms carried by said table and disposed to singly engage said lever, pivoted latch elements arranged to overlie said table incident to the shifting of said belt, and manually operable means for releasing said latch elements, and reshifting the belt as and for the purpose specified. 15

In testimony whereof we affix our signatures.

JOHN M. ANGLE.
WILL R. LYNN.
